UNITED STATES PATENT OFFICE.

CHARLES T. SCHONDELMEIER, OF BROOKLYN, NEW YORK.

DESIGN FOR A BOTTLE-STOPPER BULB.

SPECIFICATION forming part of Design No. 26,064, dated September 22, 1896.

Application filed March 10, 1896. Serial No. 582,655. Term of patent 14 years.

To all whom it may concern:

Be it known that I, CHARLES T. SCHONDELMEIER, a citizen of the United States of America, residing at Brooklyn, Kings county, 5 and State of New York, have invented a certain new and original Design for a Combined Liquid-Dropper and Bottle-Stopper, of which the following is a specification.

The present invention relates to a design 10 for a bottle-stopper and liquid-dropper bulb represented in the accompanying drawings, in which—

Figure 1 is an elevation showing my design. Fig. 2 is a vertical central section of the stopper and bulb.

The leading feature of my design is the upper semispherical hollow bulb *a*, rising by a cylindrical portion *a'* vertically from a horizontal flange or protuberance *c*, of thick discular contour, with a rounding edge which 20 finally merges into a cylindrical slightly-tapering lower projection or stopper *d*. The slightly-tapering projection *d* has a central hole in which the upper end of the dropper-

tube *e* may fit. The thick discular protuberance *c* and the slightly-tapering projection *d* are comparatively rigid, while the semi-spherical hollow bulb and cylindrical portion rising from the protuberance are more or less flexible, but the whole is sufficiently rigid to 25 be handled without danger of compressing said bulb until such pressure is desired to eject the drop. The slightly-tapering stopper portion *d*, carrying the dropper-tube, may tightly fit within the neck of any suitable 30 bottle with the tube *e* projecting down more or less near the bottom of the bottle.

What I claim is—

The design for a bottle-stopper and liquid-dropper bulb substantially as shown and described.

In witness whereof I have hereunto signed my name in the presence of two witnesses.

CHARLES T. SCHONDELMEIER.
